UNITED STATES PATENT OFFICE.

FRANK F. MILLER, OF YANKTON, SOUTH DAKOTA.

HINGE.

1,169,274.

Specification of Letters Patent. Patented Jan. 25, 1916.

Application filed May 27, 1914. Serial No. 841,309.

To all whom it may concern:

Be it known that I, FRANK F. MILLER, a citizen of the United States, residing at Yankton, in the county of Yankton and State of South Dakota, have invented certain new and useful Improvements in Hinges, of which the following is a specification.

This invention relates to door hinges, and more particularly to an improvement in the hinge shown in my Patent No. 1,091,584, issued March 31, 1914.

More specifically speaking, the present invention is an improvement in hinges of that type employed in hanging barn and similar doors, and particularly doors that are constructed of boards disposed edge to edge horizontally.

It is one aim of the invention to provide a hinge of the type mentioned so constructed that the door hung thereby will be securely held against sagging and against being torn loose from its frame.

Another aim of the invention is to provide a hinge so constructed that any desired number of hinges may be employed and mounted upon a single pintle, which serves to properly align the hinges and to further prevent sagging of the door.

The invention also aims to provide a hinge so constructed that the member thereof which is to be secured to the door frame, will require but a single bolt for its attachment, the bolt being adapted to be readily assembled with the member and disconnected therefrom, and the bolt opening being so located as not to materially weaken the member.

As before stated, the hinge embodying the present invention is so constructed that a number of them may be employed in hanging a door, and this feature adapts the hinge for use in hanging doors comprising an upper and a lower section. In this connection the invention contemplates so constructing the door carried members of the hinges that when employed in connection with a door comprising an upper and a lower section, the lower section may be lifted to adapt it to be swung over snow drifts or other obstructions, and to permit of the passage therebeneath of small stock.

In the accompanying drawings: Figure 1 is a view in elevation of several of the hinges embodying the present invention arranged to support a single door. Fig. 2 is a view similar to Fig. 1, illustrating the hinges ar-

ranged to support a door comprising upper and lower sections, the upper section being shown swung open and the lower section being shown in dotted lines in lifted position. 60 Fig. 3 is a perspective view of the door carried member of the hinge. Fig. 4 is a similar view of that member of the hinge which is carried by the door frame. Fig. 5 is a fragmentary rear elevation of the hinge 65 member shown in Fig. 4.

Corresponding and like parts are referred to in the following description and indicated in all the views of the accompanying drawings by the same reference characters. 70

As before stated, the hinge embodying the present invention is particularly designed for use in hanging doors made up of a number of boards disposed horizontally edge to edge, these boards being indicated 75 in the drawings by the numeral 1. These boards 1 are assembled and secured together in the manner shown and described in my above-mentioned patent and hence the manner of assembling and securing them will 80 only be briefly described herein. At the points at which the hinges are to be located, the meeting-edges of the boards, at that side of the door which is to be the hinged side, are cut away, as indicated at 2, and notched, 85 as indicated at 3, and angle iron bars 4 are secured to opposite faces of the door and extend vertically and have one edge of their attached wings registering with the said notches. That member of each hinge which 90 is carried by the door comprises a web 5 which is flat sided and which is provided at one edge with an integral check portion 6 which projects above and below the plane of the web and extends from one end of the 95 said edge of the web to a point adjacent the other end thereof. A cheek member 7 is formed integral with the opposite edge of the web 5 and this latter cheek member projects beyond the first-mentioned end of 100 the web and is formed with an eye 8 to engage the pintle of the hinge, as will be presently explained. A bracing and reinforcing web 9 is formed integral with the outer face of the cheek portion 7 and with the eye 8, 105 the eye being offset with relation to the plane of the said cheek portion. At its other end, the web 5 is formed with an abutment portion 10 which occupies a vertical plane at right angles to the planes occupied by the cheek portions 6 and 7, and this abutment portion projects above and

below the said end of the web 5. In assembling the member with the door, it is disposed with its web 5 lying within the cut-away portions 2 of the edges of the boards and with the projecting parts of its abutment portions 10 lying within the notches 3. The abutment portion 10 projects also at its side edges beyond the edges of the web 5, and these projecting edge portions engage against the edges of the attached wings or flanges of the angle iron bars 4. In this manner the said hinge members are securely anchored to the door and are prevented against displacement in any direction, it being understood that the cheek portions 6 and 7 rest against opposite edges of the boards between the edges of which the web 5 of the hinge member is secured.

That member of each hinge which is secured to the door frame, comprises an attaching leaf 11 formed at one end with a laterally offset eye 12 braced by a web 13 which is integral with the eye and with one face of the said attaching portion. At one point in its line of juncture with the face of the attaching portion 11, the web 13 is notched, as indicated at 14, and at this point, the attaching member is formed with an opening 15 which is substantially of mushroom form, the narrowed portion of the opening being indicated at 16. The bolt which is employed in securing this member to the door frame is indicated by the numeral 17 and is of the ordinary form having a rounded head. In assembling the bolt with the member, the bolt is disposed substantially parallel to the portion 11 and its head and the adjacent portion of its shank are caused to enter the opening 15, the bolt being rotated about its head, as a center, as it is inserted into the opening. The notch 14 of course permits of such insertion of the head end of the bolt in the opening 15 and when the bolt has been rotated to extend at right angles from the attaching portion 11, its head will be prevented from passing through the opening. The shank of the bolt is then inserted through an opening bored through the upright of the door frame, and a nut is threaded upon the bolt and tightened.

As before stated, any desired number of hinges may be employed in hanging a door depending of course upon the type of door, its weight, and its height and width. In hanging a single door, such as shown in Fig. 1 of the drawings, the required number of hinge members shown in Fig. 4 are secured to the upright of the door frame in the manner above described with the eyes 12 in vertical alinement. The door is then supported with the eyes 8 of its hinge members resting upon the eyes 12 of the frame carried hinge members and the pintle of the hinge, which comprises a suitable length of pipe or rod

material, indicated at 18, is inserted through the eyes. Where the hinges are to support a door comprising an upper and a lower section, the sections comprising the door are hung in the manner above described and so that when the sections are closed, the lower edge of the upper section will lie close to or meet the upper edge of the lower section. By reference to Fig. 2 of the drawings, in which such a door is illustrated, it will be observed that there is a space between the eye 8 of the upper hinge of the lower door section and the eye 12 of the lower hinge of the upper section. Inasmuch as the eyes of the hinge members loosely engage the pintle 18, it will be apparent that the lower section may be lifted, as illustrated in dotted lines in the said Fig. 2, when it is desired to swing this section over a snow drift or other obstruction, the upper section having of course been first swung to open position; or it may be desirable to lift or raise the lower section to permit small stock to pass beneath the same.

It will be understood from the foregoing that the narrowed portion 16 of the opening in the hinge member 11 permits of the adjustment of this hinge member with respect to the bolt 17, should the door not fit tight at the hinge connection or should the bolt opening in the door frame have been bored at the wrong place and in order that the hinge member will be prevented from slipping, after the bolt has been tightened, the rear face of the member is formed with serrations 11'.

It will furthermore be understood from an inspection of the drawings and from the foregoing description of the invention that inasmuch as the pintle employed is common to all of the hinges, the hinges will be securely held in alinement with each other in every position of the door. Furthermore the weight of the door exerts a pull upon the set of hinges directly in the vertical plane of the door as distinguished from the pull exerted to one side or the other of this plane in the use of the ordinary hinge, and this strain is evenly distributed between the several hinges due to the provision of the angle bars 4 and the manner in which the hinge members 5 coöperate therewith.

Having thus described the invention, what is claimed as new is:

1. As a new article of manufacture, a hinge member comprising a web having door-face-engaging cheek portions integral with its lateral edges, and having an eye integral with one end of one of said cheek portions and laterally offset with respect thereto.

2. As a new article of manufacture, a hinge member comprising an attaching portion having an eye and provided with a reinforcing web integral with one face of the

portion and formed at a point in the line of juncture with the said face with a notch, the said attaching portion being formed with an opening located opposite the notch.

- 5 3. As a new article of manufacture, a hinge member comprising an attaching portion having an eye and provided with a reinforcing web integral with one face of the portion and formed at a point in the line 10 of juncture with the said face with a notch, the said attaching portion being formed with

an opening located opposite the notch, the said opening having its wall of an outline approximately corresponding to the outline of a vertical section through the head end 15 of a bolt.

In testimony whereof I affix my signature in presence of two witnesses.

FRANK F. MILLER. [L.S.]
